(57) CLAIM

The ornamental design for a golf club head, as shown and described.

DESCRIPTION

FIG. 1 is a first perspective view of an embodiment of a golf club head according to the present design;

FIG. 2 is a second perspective view of the embodiment of FIG. 1;

FIG. 3 is a back elevational view of the embodiment of FIG. 1;

FIG. 3A is a cross-sectional view of the embodiment of FIG. 1, corresponding to section 3A of FIG. 3;

FIG. 3B is a cross-sectional view of the embodiment of FIG. 1, corresponding to section 3B of FIG. 3;

FIG. 3C is a cross-sectional view of the embodiment of FIG. 1, corresponding to section 3C of FIG. 3;

FIG. 4 is a front elevational view of the embodiment of FIG. 1;

FIG. 5 is a top-plan view of the embodiment of FIG. 1;

FIG. 6 is a bottom-plan view of the embodiment of FIG. 1;

FIG. 7 is a left-side elevational view of the embodiment of FIG. 1; and,

FIG. 8 is a right-side elevational view of the embodiment of FIG. 1.

Phantom lining, where utilized, is for illustrative purposes only and forms no part of the claimed design.

The cross-hatched portions of FIGS. 3A and 3B are for illustrative purposes only and the cross-hatched portion of the golf club forms no part of the claimed design.
